UNITED STATES PATENT OFFICE.

JOHN A. HOLMQUIST, OF JOHNSTOWN, PENNSYLVANIA.

WIRE-NETTING MACHINE.

1,089,054.

Specification of Letters Patent.

Patented Mar. 3, 1914.

Application filed March 28, 1912. Serial No. 686,831.

To all whom it may concern:

Be it known that I, JOHN A. HOLMQUIST, a citizen of the United States, residing in the city of Johnstown, county of Cambria, and 5 State of Pennsylvania, have invented certain new and useful Improvements in Wire-Netting Machines and the Manufacture of Wire Fencing Thereby; and I do hereby declare the following to be a full, clear, and 10 exact description of the invention, such as will enable others skilled in the art to which it appertains to make and use the same.

My invention relates to wire-fence machines and to the manufacture thereby, of 15 wire-netting with substantially polygonal-shaped meshes, in which the wires are continuous throughout the length of the fence, being twisted or interwoven together as they travel through the machine.

20 One of the principal objects of my invention is to form the fencing or netting by twisting the wires together as they are continuously advanced through the machine, thus producing the fabric with great regularity and rapidity.

25 Another object of my invention is to feed the wires, from convenient reels or coils containing large quantities of wire, into direct twisters, which, while capable of rotation in either direction, are mounted in a stationary 30 framework without lateral or longitudinal movement, said twisters being adapted to produce a righthand, and then by a reverse movement, produce a lefthand twist of the same amount, and vice versa, thereby preventing the entanglement of the stock wires in the rear of the machine.

Another object is to provide another series 35 of twisters, each capable of making what is known as a reverse twist, that is:—one in which portions of the wires immediately in advance of the twister, assume spiral forms, while at the same time, rear portions of the wires, immediately behind the twister, assume spiral forms of the opposite hand. Thus each of these reverse twists is composed of two parts, one of which is righthand spirals and the other lefthand spirals connected at the center of the twist.

40 Another object of my invention is to so arrange the mechanism for conducting these two kinds of twisting operations, that they are performed at the same time, thereby making one row of each kind of twists across 45 the fabric substantially simultaneously,

which further conduces to speed of manufacture.

Another object of my invention is to provide a revolving framework or drum for carrying and operating the reverse twisters, 60 during the revolution of said framework, whereby, in coöperation with the direct twisters, the fabric is formed continuously during its progress through the machine.

Another object is to so construct and arrange the direct twisters that they also serve as means for directly placing and holding the wires in such positions that they will be properly received by the reverse twisters as these latter revolve with their drum, thereby 70 obviating the necessity of providing independent shifting mechanism for transferring the weft-wires from side to side, as has been heretofore customary.

By means of my invention wire-netting 75 or fencing may be made with continuous substantially straight edges or selvage wires, which may be either single, double or triple, and with meshes of general hexagonal form between the marginal selvage wires; and in 80 addition to this, it may be constructed with substantially straight intermediate wires running longitudinally through the centers of the hexagonal meshes, thereby strengthening the fabric and making it more rigid 85 and capable of being thoroughly stretched on the posts or supports for its ultimate use, without sagging or narrowing.

Other objects and details of my invention will hereinafter appear. 90

Referring now to the accompanying five sheets of drawings which form part of this specification and in which like characters denote like parts: Figure 1 is a rear elevation of the machine, Fig. 2 is an elevation of 95 that side which is at the left of Fig. 1, Fig. 3 is a vertical transverse sectional elevation taken on the line III—III of Fig. 1. Fig. 4 is a rear elevation of the top of the machine showing the revolving twisting-drum carrying the rotatable reverse twisters and part of the mechanism for operating the same; the stationary bearing-bar containing the first series of direct twisters having been removed to more 100 clearly show the construction and operation of said twisting-drum. Fig. 5 is a transverse section of a portion of the twisting-drum taken on the line V—V of Fig. 6. Fig. 6 is a longitudinal section of a por- 110

tion of the twisting drum, showing one of the supporting members for the reverse twisters removed therefrom, the rack-bar operating said twisters being shown in elevation. Fig. 7 is a longitudinal section of one of the reverse twisters taken in a plane at right angles to the longitudinal section thereof, shown in Fig. 5, in order to fully illustrate this portion of my apparatus. Fig. 8 is a rear elevation of the upper part of the machine, the cap-member of the stationary bearing bar for the direct twisters having been removed for clearness of illustration. Fig. 9 is a vertical transverse section taken on the line IX-IX of Fig. 10, one of the tubular twisting fingers being shown in section and its mate, mounted in the same twister-head, being shown in elevation. Fig. 10 is an illustration of a portion of the stationary bearing-bar for the direct twisters with the rear cap-member removed therefrom, showing the rear of the said twisters, their gears and the actuating rack therefor. Figs. 11, 12, 13 and 14 are detailed views of portions of the twisting mechanisms showing the different positions which the wires assume as they pass into the machine and through the twisting mechanisms thereof; indicating the operations of twisting as follows:—Fig. 11 shows the positions of the wires before the twisting operations begin, Fig. 12 shows the positions of the wires after the first set, or direct twisters, have been turned one rotation. It should be noted that beginning with the positions shown in Fig. 11, the first half rotation of the twisting fingers lays the adjoining wires across each other and across the intermediate strand-wires, in case these latter are used. Fig. 13 shows the positions which the wires assume after the first set or direct twisters have rotated three times, thus completing their work for the row of direct twists shown in this drawing, and the second set or revolving rotary reverse twisters have accomplished part of one rotation and a part of a revolution with the drum. Fig. 14 shows the positions which the wires assume just before they enter the advancing line of receiving-notches on the revolving twisting-drum, the tubes of the direct twisters having been previously turned about three rotations as heretofore stated; and the secondary or revolving rotary reverse twisters have finished about one rotation and a further fraction of a revolution with the drum, thereby continuing their work on the row of reverse twists shown in the upper part of this figure. This reverse twisting is completed just before the wires pass from the lower part of the drum as shown in Fig. 3. Although in the illustrations, the direct twists are each shown as formed by about three turns of each twisted wire; and the reverse twists

are each shown as formed by about two turns of the wires on each side of the middle of the twist, one side being about two turns of left spirals, and the other side being about two turns of right spirals, I wish it understood that my machine and manufacture may be adapted to make any number of turns desired, in any of the twists to best serve the purpose intended. This I can accomplish by adapting or adjusting the twisters to rotate any desired number of times during their operation, as will be readily understood. Fig. 15 is a fragmentary detail view of a portion of one style of my finished wire-netting or fencing, showing at the lefthand side, the marginal strand-wire, which may be single, as drawn, or may be double or triple, and twisted into cable form as desired. In this illustration the meshes are shown as hexagons, divided however, into two parts by intermediate longitudinal strand-wires, about or with which the other fabric wires or weft-wires are coiled as shown. Fig. 16 is a fragmentary view of a portion of another style of netting or fencing made on the machine, in which the intermediate longitudinal strand-wires are not used, the meshes in this case being substantially hexagonal. Fig. 17 is a fragmentary view of a portion of a fabric made by the machine, showing a straight selvage or marginal wire and the mesh-wire coiled around the same in alternating right-hand and lefthand twists. Fig. 18 is a detailed view of a marginal direct twister showing a straight selvage or marginal strand-wire passing through the center thereof, and a mesh-wire coiled around the same by the diagonal tubular finger of said twister. Fig. 19 is a detailed view of a somewhat slightly different form of marginal twister to accomplish the same result as shown, the strand-wire in this case passing eccentrically through the body of the twister, but issuing concentric therewith, through the end of the inwardly deflected tubular finger thereof, as shown.

Referring now to the characters of reference on the various drawings which form part of this specification:—The base of the machine is indicated at 1, which may be set upon a suitable foundation and secured thereto by anchor bolts as shown; mounted on this base are the two side-frames 2, which are of somewhat similar construction, but right and left. The base 1 also supports the side-standard 3 which carries a pillow-block or bearing for the driving-shaft 4 as shown. The side-frames, as shown; are provided with various recesses, supporting ribs, seats and bearings, in or on which are mounted the various parts and mechanisms of the machine, and means are provided for securing and adjusting the same thereto. On the end of the driving-

shaft 4 the main-driving-belt-pulley 5 is mounted and provided with the main-driving-belt 6 connected with any suitable source of power; not shown. On an intermediate portion of the driving-shaft 4 the main-driving-gear 7 is mounted, which meshes with the gear 8 mounted on the intermediate shaft 9. On the other end of the shaft 9 is mounted the gear 10 which meshes with the gear 11, which latter gear is mounted and secured on the end of the twisting-drum-shaft 12. The revoluble twisting-drum, indicated in general as 13, is mounted on the drum-shaft 12 and carries a plurality of rotary twisters 14, each of which has a twisting slot 15 and a wear plate 16, these twisters being adapted to rotate by the gear-teeth 17, which form part thereof. The twisters 14 are mounted and supported in the bearing-members 18, which are shown as of L-section, but may be of any other convenient shape. The bearing-members 18 are provided with longitudinal grooves 19 therein and with circular openings 20, which form bearings for the twisters 14.

The supporting members 18 are shown in pairs secured in place and together by means of bolts as shown, whereby the twisters may be mounted or demounted as desired, for replacement or repair. In the reentrant angle of each of the supporting members 18 are the notched or beveled openings 21 opposite each end of each twister 14, said beveled openings being to provide the necessary clearance and form substantial parts with which the wires may contact, and also serve as passages for supplying oil to the bearings of the twisters 14. The bearing-members are also provided with a plurality of tapered notches 22 formed therein opposite the center of each of the twisters 14, said notches forming receiving guides wherein the advancing wires pass into the twisters during the revolution of the twisting-drum and eventually pass out of the same, as said drum continues its revolution as indicated generally on Fig. 3 of the drawings.

50 A number of rack-bars 23 are slidably mounted on the twisting-drum and provided with teeth 24, which teeth mesh with the gear-teeth 17 of the rotary reverse twisters 14. The ends of the rack-bars 23 are provided with offset portions 25 on which are revolvably mounted anti-friction rollers 26 which are adapted to contact with and be operated by the stationary twisting-cam 27 secured to the frame of the machine as shown, and the anti-friction rollers on the other ends of the said rack-bars are adapted to contact with and be operated by the stationary return-cam 28, secured to the opposite frame. The operation of said rack-bars and the consequent rotation of the re-

verse twisters 14 is accomplished by the revolution of the twisting-drum in co-operation with the twisting-cam 27 and the stationary return-cam 28, as heretofore described.

The stationary bar which serves to rotatably support the direct twisters is indicated as 29 and is provided with a forward portion 30 having a groove 31 formed therein; 32 is the removable side cap-member of the bearing-bar 29 and 33 is a groove formed therein. The rack-bar 34 is slidably mounted in the grooves 31 and 33 as shown, and is provided with teeth 35 on a portion of the upper edge thereof, which mesh with gears 36 on the ends of the stationary direct twisters 37. The intermediate cylindrical spindle portion of the direct twisters is indicated at 38, while 39 are circular holes in the stationary bearing-bar which form bearings for said direct twisters; oil for the lubrication of which, is supplied through the oil-hole 40. The direct twisters are each provided with an enlarged cylindrical head 41 shown as formed integral with the intermediate cylindrical spindle portion thereof, while 42 represent cylindrical holes in the forward portion of the bearing-bar 29 to receive and form bearings and supports for said enlarged heads 41. The intermediate rotary direct twisters are each provided with a pair of tubular fingers 43 arranged diagonally flaring, with their ends spaced apart to correspond with the mesh and twist desired.

44 are central holes through the direct twisters for the passage of the strand-wires therethrough.

43^a is a straight twister-finger of the marginal direct twister, the end of which is eccentric with the twister so as to produce a certain amount of twist in the marginal or selvage wire, as the mesh-wire is being wound with it, as shown in Figs. 11 to 16 inclusive.

As shown in Fig. 19, 43^b is a marginal twister-finger, the delivery end of which is concentrically located with respect to the twister for delivering the marginal strand-wire straight, without twisting.

45 are the substantially straight selvage or marginal strand-wires which are delivered concentrically of the marginal twisters, as described herein. The intermediate 120 strand-wires, where used, are marked 45^b and enter through holes 85 in the members 30 and 32.

45^a are selvage strand-wires which are delivered eccentrically by the marginal twister 125 and are thereby intercoiled or twisted with the mesh-wires as shown at 48^a and 49^a, this form being made by the marginal direct twisters shown in Figs. 11 to 14 inclusive.

46 are mesh-wires or weft-wires, and 47 130

are holes in the twisters 37 through which the said mesh-wires 46 pass.

48 are righthand twists each composed of a mesh-wire coiled around a selvage wire, this form being produced when the selvage wire passes through the center hole 44 of the marginal direct twister or through the concentric arm 43^b of the marginal direct twister.

10 49 are lefthand twists, but otherwise the same as the twists 48.

48^a are righthand twists, each formed of a selvage wire and a mesh-wire which are twisted together and around each other by 15 the form of marginal twister shown in Figs. 11 to 14 inclusive.

49^a are lefthand twists, but otherwise the same as the twists 48^a.

48^b are intermediate righthand twists of 20 the weft-wires made by the form of intermediate direct twisters shown in Figs. 3, 9, 11, 12, 13 and 14; while 49^b are intermediate lefthand twists of the weft-wires, but otherwise the same as the twists 48^b.

25 50 are intermediate reverse twists formed by the reverse twisters 14.

It will be noted that the direct twists extend in a substantially continuous row across the fabric, while the next rows of direct 30 twists on either side thereof, are of the opposite hand. The reverse twists as shown are composed of duplex spirals, one end of each being formed of righthand spirals and the other end of each twist being formed of 35 lefthand spirals. It should also be noted that the direct twists 48^a and 49^a when made in connection with the marginal wires 45^a, are, as shown in Figs. 15 and 16, each composed of two spirals intercoiled about each 40 other, that is:—the marginal wire is coiled around the weft-wire, and the weft-wire is also coiled around the marginal wire, thus making a very secure connection. This may be accomplished by the action of the tubular 45 fingers of the marginal twister shown in Figs. 11 to 14 inclusive, which are eccentric with respect to said twister, thereby coiling said marginal wire and welt-wire around each other to the degree shown. It should, 50 however, be further noted, that by increasing the tension of the marginal or strand-wires, in any case, these may be maintained substantially straight as and where the mesh-wires are coiled around them. It should, 55 however, be noted that by decreasing the tension of the strand-wires, in any case, they may be made wavy, or to assume a spiral form as and where the weft-wires are coiled with them, thereby forming twists in both 60 of these wires and thereby more securely locking them together, if desired. Thus by the operation of the mechanism shown, or by the adjustment of the operation thereof, or by a combination of said mechanism and

adjustment, any of the styles of direct twists 65 shown herein may be made.

A form of netting is shown in Fig. 16 from which the intermediate longitudinal strand-wires are omitted, thereby forming a netting with substantially hexagonal 70 meshes, and this form, as well as that shown in Fig. 16, may be made on the machine.

By varying the distances between the twisters and between the other parts of the mechanism which operates between the various wires, a netting of any size, mesh or proportion can be made, and in case where the machine is constructed to make a wide fabric, it may be made to make two or more narrower strips at the same time. The sizes 80 of the wires used may also be varied and any pre-determined number of twists may be made at each intersection to best accomplish the purpose intended. The meshes may also be made longer or shorter by arranging the coiling mechanisms at different distances longitudinally and timing their 85 operation accordingly, by the adjustment of the gearing and other mechanisms, as will be readily understood.

90 On one end of the shaft 9 is mounted the bevel-gear 52 which meshes with the bevel-gear 53 mounted on the shaft 54 on which latter shaft a crank-arm 55 is secured as shown. A connecting-rod or pitman 56 is 95 pivotally connected to the crank-arm 55 by means of the bolt 57 as shown. Another cylindrical-hole 58 is provided in the connecting-rod 56 for the purpose of shortening and adjusting the stroke thereof by connecting it to the crank-arm 55 through another hole 59 as shown, which is slotted in form to allow for radial adjustment. When the connecting-rod 56 is connected to the crank-arm 55 through the supplementary holes 58 100 and 59, the stroke of the said rod is shortened and a lesser number of rotations is then made by the direct twisters 37 operated thereby. This means of adjustment is provided so as to vary the number of turns of 105 the wire made by the direct twisters and thereby vary the product in a predetermined manner; and also for the purpose of exactly adjusting the number of rotations made by these twisters for any particular form of 110 fabric. This adjustment may be made in coöperation with the adjustable connection of the pitman 56 to the arm 61 of the toothed-sector 63 which operates the direct twisters. The opposite end of the connecting-rod 56 is provided with an elongated slot 60 in which are adjustably mounted the bearing-blocks 65 adapted to contact with 115 and serve as bearings for the bearing-pin 64 which pin is mounted on an intermediate 120 portion of the radius-arm 61 of the toothed-sector 63 which latter is pivoted at its lower end as shown at 62. The bearing-blocks 65

- are mounted within the elongated slot 60 and provided with bolts 66 for adjusting their location longitudinally therein in any position desired. The jam nuts or internally threaded collars 67 act in coöperation with the nuts 68 mounted on the bolts 66 in such a way as to hold the blocks 65 in the positions desired. Owing to the limitation of the drawings, the bolts 66 are shown somewhat short to give only a limited adjustment to the bearing-blocks 65, but it may be readily understood that these bolts may be made as long as desired, to give greater adjustment, if required. On the stub-shaft 70 a pinion 69 is mounted, which pinion meshes with the toothed-sector 63, and on the same shaft the gear-wheel 71 is mounted and adapted to mesh with the teeth 51 on the lower edge of one end of the rack-bar 34. The direct twisters are rotated by these mechanisms:—first in one direction, and then are stationary while a certain amount of lengths of wires are traversed through them; after which they are rotated in the opposite direction; these operations being then repeated in sequence for the formation of the direct twists shown on the drawings. As the connecting-rod or pitman 56 moves forward one of the bearing-blocks 65 contacts with the bearing-pin 64 and moves the toothed-sector 63 in one direction, thereby rotating the direct twisters in a corresponding direction; while during the first part of the return movement of the said connecting-rod, the toothed-sector remains stationary, thereby causing the direct twisters to stand without rotating for a time; until by the continuation of the return movement of said connecting-rod, the opposite bearing-block 65 contacts with the bearing-pin 64, whereby the further return movement of said rod rotates the direct twisters in the opposite direction; whereupon this sequence of operations is repeated. This, therefore, makes the direct twists of netting of styles and dispositions shown on the drawings.
- On one of the outer ends of the twisting-drum-shaft 12 a pulley 72 is mounted, which connects, by means of a belt 73, with the flanged belt pulley 74 mounted on the end of the stub-shaft 75 for the purpose of driving the same. The stub-shaft 75 is provided with a socket to receive and drive the winding-barrel 76, which is temporarily secured thereto in the customary way by a key as shown, and the finished netting is wound on the winding-barrel 76 which is of usual construction. The belt 73 which drives the winding-barrel 76 is provided with a tension-roller 77 revolvably mounted on an arm 78, actuated by a lever 79, provided with the grip-member 80 and the pawl 81 attached thereto. The ratchet-bar 82 coöperates with the pawl 81 to hold the belt-roller 77 in position as desired; while on the lever 79 is the guide-plate 83 adapted to slidably hold the same in connection with the ratchet-bar. An idler supporting-roller 84 is also provided, around part of the circumference of which the netting passes as it travels from the twisting-drum to the winding-barrel. As the roll of finished netting increases in size on the winding-barrel 76, the belt 73 may be slightly slackened by the belt-tightener or tension-roller 77 and its appurtenances, so that the said belt will slide somewhat over its pulleys while at the same time maintaining the required degree of tautness in the roll of netting.
- Having thus given the foregoing description of the machine and the operation of the various parts, I will now further describe and summarize the operations of manufacture.
- The various wires required for the manufacture of the netting are led to the machine directly from convenient coils or reels in the rear thereof, which, for convenience of illustration, are not shown. Means may be provided to produce more or less tension in said wires as they are drawn into the machine, said tensions being varied to best produce the desired results. The intermediate holes 85 are provided for their introduction in cases where intermediate longitudinal strand-wires are used; these are led through the central openings 44 in the direct twisters, while the mesh-wires or weft-wires 46 are led through the lateral holes 47 and thence issue from the extremities of the diagonal intermediate tubular fingers 43. The marginal wires are led through the marginal twisters either concentrically or eccentrically, as desired, as heretofore described. The wires then pass over the twisting-drum 13 on which the fabrication is completed and the finished netting then passes around a portion of the idler-roller 84 and is wound in a roll on the winding-barrel 76. The twisting mechanism of the twisting-drum 13 serves to make the reverse twists and also clamps the wires therein to draw them through the machine with a uniform and continuous motion, and as this is done, the direct twisters 37 and the tubular fingers thereof, coil the weft-wires around each other and around the intermediate wires and the marginal wires. After one row of these direct coils is completed across the fence, the direct twisters remain stationary for a time, due to the intermittent movement of their operating mechanisms occasioned by the action of the slotted connecting-rod 56 as heretofore described. While the direct twisters are stationary, the twisting-drum continues to pull the wires forward and when this has been accomplished to the required degree, the direct

twisters are rotated in a reverse direction by their actuating mechanisms, thereby forming the next row of direct twists of the opposite hand. The direct twisters are then again stationary for a time, as before, whereupon the sequence of their operations is repeated. After a row of direct twists is made as described, the tubular fingers of the direct twisters remain stationary for a time and hold the wires in the positions shown in Figs. 13 and 14 and are thereby caused to enter the receiving notches 22 by the revolution of the twisting-drum as it turns continuously. The continued revolution of the twisting-drum causes the wires to be advanced and finally seated in the reverse twisters 14 as shown in Fig. 11. The further continuation of the movement of the twisting-drum causes the rollers 26 of the rack-bars 23 to contact with the twisting-cam 27, thereby rotating the reverse twisters 14 in one direction, which motion is continued as the twisting-drum revolves, so that before the wire issues from the same, the rows of the reverse twists 50 are formed. After the wires have issued from the twisting-drum as shown in Fig. 3, the rollers 26 on the other ends of the rack-bars 23 contact with the return cam 28 and said rack-bars are thereby returned to their first positions ready for another operation.

The reverse twisters on the drum 13 are located intermediate of or between the corresponding direct twisters, so that the centers of the reverse twisters on the drum are longitudinally opposite the median space between two corresponding direct twisters; the tubes of the direct twisters containing the mesh-wires are inclined as shown, whereby the mesh-wires are twisted around each other, and then, by the stoppage of the direct twisters in the positions shown in Figs. 14 and 11, the mesh-wires are placed and held in line for direct reception by the receiving-notches 22 and the reverse-twisters 14. By reason of this construction and arrangement no separate shifting mechanism is required to move the weft-wires from one side to the other, as has been customary heretofore.

I prefer to stop the rotations of the direct twisters when the tubular fingers thereof are somewhat above and below a horizontal plane passing through their axes of rotation. When this is done the contiguous fingers of the adjacent twisters are near together, one diagonally above the other, thereby holding one weft-wire above, and the other below said plane and presenting the wires in positions to enter the advancing receiving-notches of the twisting-drum and pass thence into the narrow slots of the reverse twisters in a pre-determined order, as these slots are preferably slightly wider than the diameter of one wire and considerably narrower than

the combined diameter of two wires, so that when two or more wires pass into the slots, they must do so in sequence. By this means the wires are also seated in each of the reverse twisters in a pre-determined order, 70 namely:—the weft-wire issuing from the lower tubular finger enters first, then the intermediate strand-wire, if used, and then the weft-wire from the upper tubular finger. By stopping the tubular fingers in the positions just described and by timing their stoppage, with due regard to the advancing receiving-notches of the twisting-drum, regular and uniform twists and meshes are insured. As the twisting-drum 13 revolves 80 it carries with it the fabric in process of formation, the final twisting of which is completed, before it leaves the drum as shown in Fig. 3. After leaving the drum the fabric passes behind the idler-roller 84 and is wound in a roll on the winding-barrel 76 as heretofore described.

For convenience of illustration and description I have shown the machine with the direct twisters side by side with their rotation axes parallel and in a horizontal plane, and with the axis of the twisting-drum located horizontally, but I wish it understood that these arrangements and those of the other parts, may be modified and that the 95 relative or absolute positions of the various mechanisms may be varied, without departing from the spirit of my invention. To facilitate clear illustration, the marginal strand-wires or selvage wires are shown as 100 single wires, but these may be composed of two or more wires previously twisted into cable form, if desired.

Although I have described and illustrated my invention in considerable detail, I do not 105 wish to be limited to the exact and specific details thereof, as shown and described, but may use such modifications in, substitutions for, or equivalents thereof, as are embraced within the scope of my invention, or as 110 pointed out in the claims.

Having thus described my invention, what I claim and desire to secure by United States Letters Patent is:—

1. In a machine of the character described, 115 means for continuously advancing a series of wires therethrough, means for forming a transverse row of direct twists between pairs of said wires, and means coöperating therewith for simultaneously forming a transverse row of reverse twists from differently grouped wires of said series.

2. In a machine of the character described, 120 means for continuously advancing a series of wires therethrough, means for forming a transverse row of direct twists in one direction between pairs of said wires, means for forming thereafter another transverse row of direct twists in the opposite direction between said pairs of wires, and means coöp- 130

- erating therewith for simultaneously forming transverse rows of reverse twists from differently grouped wires of said series.
3. In a machine of the character described, means for continuously advancing a series of wires therethrough, means for forming a transverse row of direct twists in one direction and thereafter another transverse row of direct twists in the opposite direction, and means coöperating therewith for simultaneously forming a transverse row of reverse twists between each of the rows of direct twists aforesaid from differently grouped wires of said series.
4. In a machine of the character described, a plurality of direct twisters provided with means for operating the same intermittently in opposite directions, in combination with a plurality of reverse twisters adapted to continuously advance a plurality of wires through said machine.
5. In a machine of the character described, means for continuously advancing a series of wires therethrough, means for alternately forming transverse rows of righthand and lefthand direct twists from the same pair of adjacent wires, means coöperating therewith for simultaneously forming transverse rows of reverse twists between, and in staggered relation with, the rows of direct twists aforesaid, and from differently grouped wires of said series.
6. In a machine of the character described, means for continuously advancing a series of wires therethrough, means for intermittently forming a row of direct twists coiled in one direction and thereafter forming another row of direct twists coiled in the opposite direction, each being formed from the same pair of wires, and means coöperating therewith for simultaneously forming transverse rows of reverse twists between each of the rows of direct twists aforesaid in staggered relation therewith, and from differently grouped wires of said series.
7. In a machine of the character described, means for continuously feeding a plurality of wires therethrough, means for twisting pairs of adjacent wires around each other in direct twists, the adjoining rows of which are of the opposite hand, means coöperating therewith for simultaneously forming transverse rows of reverse twists between the adjoining rows of direct twists, in staggered relation thereto and from differently grouped wires of said series.
8. In a machine of the character described, means for intermittently twisting pairs of adjacent wires around each other in direct twists, the adjoining rows of which are of the opposite hand, means coöperating therewith for simultaneously forming transverse rows of reverse twists between the adjoining rows of direct twists in staggered relation thereto, and from differently grouped wires of said series.
9. In a machine of the character described, means for intermittently forming transverse rows of direct twists from adjacent pairs of wires, the adjoining rows thereof being coiled in opposite directions, means coöperating therewith for forming transverse rows of reverse twists between each of the rows of direct twists aforesaid in staggered relation therewith, and from differently grouped wires of said series, and means for continuously advancing the reverse twisting means, whereby the wires are fed continuously through the machine.
10. In a machine of the character described, the combination of a plurality of direct twisters adapted to intermittently rotate in opposite directions, a plurality of rows of reverse twisters in advance of and in staggered relation therewith, means for rotating said reverse twisters and for revolving the same continuously, whereby the wires are continuously advanced through the machine.
11. In a machine of the character described, the combination of a plurality of direct twisters adapted to intermittently rotate in opposite directions, a plurality of rows of reverse twisters in advance of and in staggered relation therewith, means for intermittently rotating said reverse twisters in operative directions and oppositely in return directions and for revolving the same continuously, whereby the wires are continuously advanced through the machine.
12. In a machine of the character described, the combination of an alined row of direct twisters provided with means for intermittently rotating them in opposite directions, a plurality of rows of reverse twisters in advance of, parallel to and in staggered relation with the row of direct twisters aforesaid, means for rotating said reverse twisters and for revolving the same continuously, whereby the wires, while being interwoven, are continuously advanced.
13. In a machine of the character described, the combination of an alined row of direct twisters provided with means for intermittently rotating them in opposite directions, a plurality of rows of reverse twisters in advance of, parallel to and in staggered relation with the row of direct twisters aforesaid, said reverse twisters being adapted to grip and twist the wires, means for rotating said reverse twisters and for revolving the same continuously, whereby the wires, while being interwoven, are continuously advanced.
14. In a machine of the character described, a plurality of direct twisters provided with means for intermittently rotat-

- ing the same in opposite directions, a plurality of reverse twisters arranged in advance thereof, and mounted on a continuously revolving drum, and means for operating said reverse twisters.
15. In a machine of the character described, a plurality of direct twisters provided with means for intermittently rotating the same in opposite directions, a plurality of reverse twisters mounted on a continuously revolving drum in advance thereof, and means operated by the revolution of the said drum for operating said reverse twisters.
15. In a machine of the character described, a plurality of direct twisters provided with means for intermittently rotating the same in opposite directions, a plurality of reverse twisters mounted on a continuously revolving drum arranged in advance thereof, means operated by the revolution of the said drum for operatively rotating said reverse twisters and for oppositely rotating the same to their receptive positions.
17. In a machine of the character described, a plurality of direct twisters provided with means for intermittently rotating the same in opposite directions, a plurality of reverse twisters mounted on a revolving drum in advance thereof and adapted to grip and twist a plurality of wires, means for continuously revolving said drum, and means operated thereby for alternately rotating said reverse twisters in opposite directions.
18. In a machine of the character described, a plurality of direct twisters, means for intermittently rotating the same in opposite directions, a plurality of reverse twisters provided with gear teeth rotatably mounted on a revolute drum in advance thereof, means for continuously revolving said drum, a rack coöoperating with the gear teeth of each row of reverse twisters, a stationary twisting-cam adapted to operate said rack and a stationary return-cam adapted to return said rack, thereby operating said reverse twisters and returning them to receptive positions by the continuous movement of the drum aforesaid.
19. In a machine of the character described, a plurality of direct twisters provided with means for rotating the same, in combination with a revolute drum provided with twisting mechanism mounted thereon, adapted to be operated by the movement of said drum.
20. In a machine of the character described, a plurality of direct twisters provided with means for intermittently rotating the same in opposite directions, in combination with a revolute drum provided with twisting mechanism mounted thereon adapted to be operated by the movement of the said drum.
21. In a machine of the character described, a plurality of direct twisters, means for intermittently rotating the same in opposite directions, a revolute drum and means for continuously revolving the same, twisting mechanism mounted on said drum and adapted to be operated by the movement thereof.
22. In a machine of the character described, a plurality of direct twisters provided with diagonal tubular fingers whereby the wires are twisted and then positioned for further twisting, in combination with a plurality of reverse twisters mounted on a continuously revolving drum adapted to receive and further twist the wires as aforesaid, and means for operating the same.
23. In a machine of the character described, a plurality of direct twisters provided with diagonal tubular fingers, means for intermittently rotating said direct twisters in opposite directions and for stopping them in positions as desired, in combination with a plurality of reverse twisters located in advance of and in staggered relation therewith, means for rotating and for continuously revolving said reverse twisters, and inclined guides adapted to revolve with the said reverse twisters, whereby the wires positioned as aforesaid, are presented thereto.
24. In a machine of the character described, a plurality of direct twisters mounted in stationary bearings and provided with diagonally flaring tubular fingers, means for intermittently rotating said direct twisters in opposite directions and for stopping them in inclined positions, as desired, in combination with a plurality of reverse twisters in advance of, and in staggered relation therewith, said reverse twisters being mounted on a drum adapted to be revolved continuously, guiding means carried by said drum, whereby the wires positioned as aforesaid are presented to the reverse twisters, and means for operating said reverse twisters by the continuous revolution of said drum.
25. In a machine of the character described, means for continuously feeding a plurality of wires therethrough, a plurality of direct twisters mounted in stationary bearings and adapted to intermittently rotate in opposite directions, a plurality of rotary revolute reverse twisters located in advance thereof, and adapted to grip, twist and continuously advance the wires, and means for operating the same.
26. In a machine for making wire-netting, the combination with the direct twisters, of a revolute drum located in advance thereof and provided with means for continuously revolving the same, a plurality of

rows of reverse twisters mounted on said drum adapted to be operated by the movement thereof, a corresponding series of inclined guides fixed on said drum opposite each of the reverse twisters aforesaid, whereby the wires will be automatically fed to the reverse twisters. 5

27. In a machine for making wire-netting, the combination with the direct twisters, of 10 a revoluble drum located in advance thereof, means for continuously revolving the same, a plurality of rows of reverse twisters, arranged in staggered relation with the direct twisters aforesaid, mounted on said drum 15 and adapted to be operated by the movement thereof, a corresponding series of inclined guides fixed on said drum opposite each of the reverse twisters aforesaid, whereby the wires will be automatically fed thereto. 20
28. In a machine for making wire fabric, the combination with the direct twisters, of a continuously revolving drum provided with rotary reverse twisters mounted thereon, means for automatically guiding the 25 wires into the reverse twisters by the revolution of said drum, and means for operating said twisters. 30

29. In a machine of the class described, a continuously revolving drum, a plurality of 30 pairs of bearing members mounted thereon, a plurality of reverse twisters rotatably mounted in the bearing members aforesaid, the outwardly projecting parts of said bearing members being notched and adapted to 35 automatically guide wires into said twisters. 30. In a machine of the class described, a continuously revolving drum, a plurality of pairs of bearing members mounted thereon, a plurality of reverse twisters rotatably 40 mounted in the bearing members aforesaid, the outwardly projecting parts of said bearing members being notched and adapted to automatically guide wires into said twisters, said twisters each being provided with 45 gear teeth, a longitudinal groove formed in

the interior opposing faces of said bearing members, a toothed rack mounted in said groove, fixed cams mounted near the ends of said drum and adapted to coöperate with the racks aforesaid, whereby the twisters are 50 operated and returned to the receptive positions.

31. In a machine of the character described, a plurality of direct twisters each provided with a pair of diagonal tubular fingers, means for rotating said direct twisters and stopping them in positions as desired, in combination with a continuously revolving drum carrying a plurality of reverse twisters arranged in advance of and in 55 staggered relation with the direct twisters aforesaid, fixed guiding means mounted on said drum and adapted to receive wires from the aforesaid tubular fingers when positioned, and by the revolution of said drum present said wires to the rotary reverse 60 twisters, substantially as described. 65

32. In a machine for making wire-netting, the combination with a plurality of direct twisters and a plurality of reverse twisters 70 in advance of and in staggered relation therewith, of means for automatically guiding the wires from the direct twisters to the corresponding reverse twisters. 75

33. In a machine for making wire-netting, means for continuously advancing a plurality of wires therethrough, a series of direct twisters provided with tubular fingers adapted to twist the adjoining wires and direct them to a set of reverse twisters in advance of and in staggered relation with the direct twisters aforesaid, and means for operating the same. 80

In testimony whereof I hereto affix my signature in the presence of two witnesses. 85

JOHN A. HOLMQUIST.
